WELDER'S HOOD

Stanley H. Carlson, Seattle, Wash., assignor, by
mesne assignments, to Flex-Weld Corporation,
a corporation of Washington

Application May 23, 1944, Serial No. 536,987

4 Claims. (Cl. 2-8)

This invention relates to welders' hoods. An object of this invention is to provide in a welder's hood, a shiftable shade element which can be optionally shifted out of registry with the clear glass window by movement of the chin of the wearer.

Another object of this invention is to provide an attachment for mounting on the inside of a welder's helmet so that the helmet may be transformed to provide for optional positioning of the shade element or dark glass across the window opening.

A further object of this invention is to provide an improved operating means for shifting the dark glass, the operating means including a spring-pressed lever having a chin engaging member adjustably mounted thereon so that the device may be adapted to different persons.

A further object of this invention is to provide an improved carrier for the dark glass so that the glass can be easily replaced without taking the entire device apart.

A further object of this invention is to provide an improved lever combination connected to the prime mover and to the dark glass carrier so that a very short movement of the prime mover will provide the desired length of movement of the carrier.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawings:

Figure 1 is a detail side elevation partly broken away and in section of a welder's hood constructed according to an embodiment of this invention;

Figure 2 is a detail rear elevation of the hood;

Figure 3 is an enlarged fragmentary sectional view taken on the line 3-3 of Figure 2;

Figure 4 is a detail front elevation of the operating means for the dark glass with the front wall of the housing removed;

Figure 5 is a sectional view taken on the line 5-5 of Figure 4;

Figure 6 is a sectional view taken on the line 6-6 of Figure 4;

Figure 7 is a detail rear elevation partly broken away of the dark glass carrier;

Figure 8 is a fragmentary sectional view taken on the line 8-8 of Figure 4;

Figure 9 is a fragmentary sectional view taken on the line 9-9 of Figure 4;

Figure 10 is a fragmentary sectional view taken on the line 10-10 of Figure 3; and

Figure 11 is a fragmentary sectional view taken on the line 11-11 of Figure 3.

Referring to the drawings, the numeral 15 designates generally a hood structure embodying opposite side walls 16, arcuate top wall 17, a bottom wall 18 and a front wall 19. The front wall 19 is preferably flat whereas the opposite sides, top and bottom walls are of flared construction, flaring toward the rear. The hood 15 is supported on the head of the wearer by means of a band structure 20 which is secured or supported between the side walls 16 by means of a pivot 21.

A transparent panel 22 is mounted in a frame structure generally designated as 23. The frame structure 23 includes an inner plate 24 having an outwardly offset flange 25 extending through a window opening 26 formed in the front wall 19. A flanged bezel 27 is secured by fastening means 28 to the front wall 19, the fastening means 28 also securing the plate or inner bezel 24 to the inner side of the front wall 19.

In order to provide a means whereby a dark glass may be optionally positioned in registry with the window 26, I have provided an attachment generally designated as 29 which is secured to the inner side of the front wall 19. The attachment 29 includes a housing 30 having a marginal flange 31 which is secured by fastening members 32 to the inner side of the front wall 19. The housing 29 also includes an inner flange 33 against which a transparent panel 34 is secured by means of a bezel 35. A front wall 36, which is provided with a vertical rearwardly projecting flange 37, is adapted to engage in the forward open side of the housing 30 and is secured therein by means of fastening members 38.

A dark glass carrier or frame 39 is mounted within the housing 30 and comprises a pair of vertically disposed confronting channel members 40 which are carried by an inverted U-shaped lower frame member 41. The carrier 39 is interposed between the rear transparent panel 34 and the front wall 36 of the housing 30. A dark glass panel 42 is mounted in the vertical channel members 40, being inserted from the upper ends of these channel members so that the dark glass or panel 42 may readily be replaced when broken. A pair of longitudinally bowed springs 43 are secured to the forward side of the rear

wall 44 of the housing 30 by fastening members 45. The springs 43 are adapted to bear against the rear side of the carrier 39 so as to hold this carrier in sliding contact with the front wall 36. The housing 29 at the upper end thereof is provided with a pivoted top wall 46 which is adapted to be swung rearwardly so that the dark glass 42 may be removed from the carrier 39 for replacement thereof. The lower edge of the rear transparent panel 34 rests on a horizontally disposed angle member 47 which is secured by fastening members 48 to the rear wall 47.

A pair of rock levers 49 and 50 are rockably mounted on a pivot member 51 engaging through the rear wall 44 of the housing 29. Rock lever 49 is provided with a forwardly projecting pin or lug 52 which slidably engages in a slot 53 formed in the U-shaped frame member 41 adjacent one end thereof. Rock lever 50 is provided with a forwardly projecting pin 54 which loosely engages in a slot 55 formed in the lower frame member 41 adjacent the opposite end thereof from the slot 53. Rock lever 49 is provided with an extension 56 which extends on the opposite side of the pivot 51 from the lever 49 and is formed with forwardly projecting pin 57. Rock lever 50 is provided with an extension 58 which has a rearwardly pin 59 at the outer end thereof. A pitman 60 is disposed in the housing 29 and is provided at one end thereof with a pin or pivot member 61 engaging in an opening 62 formed in the side wall 63a of the housing 29. The pitman 60 is provided with an enlargement 63 having an elongated opening 64 within which the pivot member 51 loosely engages; so that the pitman 60 may be rocked vertically for the limit permitted by the length of this slot 64. The pitman 60 is formed with an outwardly opening slot 65 within which the pin 59 slidably engages, and the pitman 60 is also formed with a second slot 66 on the side of the pivot 51 opposite from the slot 65 and within which the pin 57 slidably engages. The pitman 60 at its lower portion, is provided with an enlargement 67 having a slot 68 formed therein, and a second pitman 69 is provided with a right angularly disposed lug 70 which engages in the slot 68. The pitman 69 is formed with a pivot 71 engaging in the side wall 72 which is opposite from the side wall 63 of the housing 29, and the pitman 69 is formed at a point between the ends thereof with a downwardly and rearwardly inclined lug or extension 73 having an opening 74 therein. A rock lever 75 which is formed with outwardly extending trunnions 76 is rockably carried by an offset housing 77 formed at the lower portion of the rear wall 44. The rock lever 75 is provided with a head 78 loosely engaging in the slot 74 so that the rocking of the lever 75 will effect rocking of pitman 69 and pitman 60. Rock lever 75 is provided at its lower end with an arcuate extension 79 on which a slotted plate 80 is adjustably mounted. The plate 80 is adjustably mounted on the arcuate extension 79 by means of a fastening member 81. The plate 80 is formed with a pair of rearwardly and downwardly extending parallel levers 82, and a chin rest member 83 is adjustably secured between the levers 82. The chin rest member 83 comprises a body 84 having a transverse opening 85 therethrough and a pair of clamping members 86 and 87 extend through the opening 85 and are provided at their outer ends with flanges 88 and 89, respectively. The levers 82 engage between the confronting flanges 88 and 89 and a coil spring 90 is posi-

tioned between the two members 86 and 87 and bears against the inner sides of the levers 82. The body 84 is split as at 91 so as to form a split clamp and a threaded pressure member 92 engages through the outer jaw 93 of the clamp and is threaded into the inner jaw 94. The rock lever 75 is constantly urged in a counter-clockwise direction by means of a spring 95. The spring 95 engages about the pivot 76, and the lever 75 is tensioned by means of a tensioning screw 96 engaging one end of the spring 95 and bearing against the lever 75. The spring 95 constantly urges the lever 75 to rock in a counter-clockwise direction and to thereby normally maintain the carrier 41 and the dark panel 42 in an uppermost operative position which is in registry with the window opening 26. The body 84 of the chin rest 83 is provided with an arcuate chin engaging member 97 which may be formed integral with the body 84 and which, as shown in Figure 1, is adapted to engage beneath the chin of the user so that downward movement of the chin will cause lever 82 to be rocked downwardly, and downward rocking of lever 82 will cause downward movement of carrier 39 to thereby move the dark panel 42 downwardly and out of registry with the window opening 26.

In the use and operation of this hood, the device is mounted on the head of the wearer in the usual manner as shown in Figure 1. In this position, the chin of the user will rest on the chin rest member 97. Spring 95 will normally maintain carrier 39 with dark glass or panel 42 in the uppermost operative position. When it is desired to move carrier 39 downwardly so as to position the dark glass or panel 42 out of registry with panels 22 and 34, the chin is rocked downwardly thereby rocking the rear portion of lever 82.

Downward rocking of lever 82 will cause lever 75 to rock upwardly at its forward end against the tension of spring 95, and upward rocking of lever 75 will raise the free end of pitman 69 causing lug 70 to raise the free end of pitman 69. Upward rocking in a clockwise direction of pitman 69 will cause the outer ends of levers 49 and 50 to rock downwardly.

The housing 29 with the elements associated therewith may be mounted on a conventional welder's hood, so as to thereby provide an attachment for the hood whereby the dark glass may be optionally moved out of registry with the clear glass window, in order that the user of the device need not continually remove the hood in order to clearly see the articles when the welding torch is not applied to the articles.

What I claim is:

1. An attachment for a welder's hood comprising a housing for attachment to the inner side of the front wall of the hood, said housing including front and rear walls and opposite side walls, said front and rear walls having aligned window openings therein, a U-shaped panel carrier slidable in said housing, a dark glass panel carried by said carrier, a top wall pivotally carried by said housing above said carrier, a pair of rock levers rockably carried by said housing, a pin carried by an end of each lever and engaging said carrier, an extension carried by each lever, a pin carried by said extension, a pitman rockably carried by said housing having slots in which said latter pins engage, a second pitman rockably carried by said housing engaging first pitman in a manner whereby rocking of said second pitman will rock said first pitman, an

extension carried by second pitman between the ends thereof, and an operating lever pivotally carried by said housing and operatively connected to said latter extension, a spring engaging said operating lever whereby to normally maintain said carrier in an uppermost operating position with said panel in registry with said openings.

2. An attachment for a welder's hood comprising a housing including a front and rear wall and opposite side walls, said front and rear walls having aligned window openings therein, a U-shaped panel carrier slidable in said housing, a dark glass panel carried by said carrier, a top wall carried by said housing above said carrier, a pair of rock levers carried by said housing, a pin carried by the end of each lever and engaging said carrier, an extension carried by each lever and a pin carried by said extension, a pitman rockably carried by said housing having

slots in which said latter pins engage, and means engaged with said pitman for operating the pitman.

3. The device as claimed in claim 2, and including a second pitman rockably carried by said housing engaging said first pitman in a manner whereby rocking of said second pitman will rock said first pitman, and means engaged with said second pitman for operating the second pitman.

4. The device as claimed in claim 2, and including a second pitman rockably carried by said housing engaging said first pitman in a manner whereby rocking of said second pitman will rock said first pitman, and an extension carried by said second pitman and an operating lever pivotally carried by said housing and connected to said latter extension.

STANLEY H. CARLSON.
